UNITED STATES PATENT OFFICE

132,673

DESIGN FOR A WEDDING RING

Philip Krasnow, New York, N. Y.

Application March 17, 1942, Serial No. 106,223

Term of patent 7 years

To all whom it may concern:

Be it known that I, Philip Krasnow, a citizen of the United States and resident of the county of Kings, city and State of New York, have invented a new, original, and ornamental Design for a Wedding Ring, of which the following is a specification, reference being had to the accompanying drawing, forming part thereof.

In the drawing:

Fig. 1 is a view, in perspective, of a wedding ring showing my design; and

Fig. 2 is a similar view of the ring turned through an angle of about 90 degrees.

The design elements shown in Figs. 1 and 2 of the drawing are alternated around the periphery of the ring.

What I claim is:

The ornamental design for a wedding ring, substantially as shown and described.

PHILIP KRASNOW.
